UNITED STATES PATENT OFFICE.

THOMAS R. SPENCER, OF LEBANON, OHIO.

SMOKE-WASHING DEVICE.

Application filed January 30, 1926. Serial No. 84,963.

The present invention relates to a device for remedying the smoke evil.

The principal object of this invention is to provide means whereby the smoke from a boiler or other furnace may be washed or freed from carbons, other solids and obnoxious substances, so that only clear, colorless and inoffensive gases may be liberated into the atmosphere.

10 Other objects of the invention will appear from the following detailed description thereof.

In the drawings:

Figure 1 is a plan view of the device.

15 Figure 2 is a sectional view of the reservoir, the operating parts being shown in side elevation.

The numeral 1 indicates an exhaust fan of any desirable construction connected by 20 means of a pipe 2 with the smoke outlet of a furnace 3. The fan 1 is driven by any convenient source of power through a shaft 4, arrangement for variable speed being made by a cone pulley 5. Provision is made for 25 cooling the exhaust fan 1 by means of a water pipe 6 communicating with any suitable source of supply, the end of said pipe being perforated to permit water to drip upon the fan. The fan 1 rests upon a concrete base 7 which forms one wall of a concrete tank or reservoir 8 in which water is maintained approximately to the level of the line 9. The exhaust from the fan 1 is carried by means of a pipe 10 to a centrifugal pump 11.

30 The pump 11 is mounted on a concrete base 12 near the bottom of the reservoir 8 and is entirely submerged in the water in said reservoir. The pump 11 besides receiving the exhaust from the fan 1 also takes in water from the reservoir through an open ended branch pipe 13. The outlet 14 of the pump 11 is connected by 35 means of a pipe 15 with the intake 16 of a second centrifugal pump 17 similar to the pump 11. The pump 17 is mounted on the concrete base 18 on a higher level than the pump 11. Inside the concrete reservoir 8 is a closed metal tank 18^a into which the pump 17 discharges through a pipe 19 and a pipe 20, which extends through the top of the reservoir 18^a.

40 The metal reservoir 18^a communicates with the reservoir 8 through screened openings 21 below the water level and thus the water is maintained in the reservoir 18 at the same level as in the main 55 reservoir 8. The pipe 20 extends below the water level in the reservoir 18^a as will be seen in Figure 2. The reservoir 18^a is provided with an outlet 22 just above the water level from which a pipe 23 leads to any suitable exhaust location. The reservoir 18^a is further provided with a drain 24 through which the water may be drained off and said reservoir cleansed when necessary. The pumps 11 and 17 are driven by means of 60 pulleys 25 from any suitable source of power and it is desirable that said pumps be driven at a slightly higher rate of speed than the fan 1.

65 It is thought that the operation of the device will be apparent to those skilled in the art to which the same appertains from the foregoing description. The smoke from the furnace 3 is exhausted by the fan 1 and carried through pumps 11 and 17. In pump 70 75 11 it is mixed with water and the operation of the two pumps causes the smoke and fumes to be thoroughly washed and the solids taken up by the water. The pump 17 exhausts into the closed reservoir 18^a 80 where the solids are deposited in the water in said reservoir and the gases permitted to be carried off through the pipe 23.

75 It will be understood that while I have shown in the construction only two washing or mixing pumps, any suitable number in order to accomplish the result may be employed in series as shown. It will also be understood that it may at times be desirable to provide for a continuous flow from the 85 reservoir 18 through the drain 24, such flow being compensated for by means of the inflow from the sprinkler pipe 6.

80 By means of the device described, it will be understood that I have provided a forced draft for a furnace and have also been able to eliminate entirely the necessity for a smoke stack or chimney.

85 It will be observed that in the mechanism shown, I have provided a means whereby 100 the smoke and exhaust fumes from a furnace may be thoroughly washed and the solids removed from the gases, the latter being liberated into the air at any desired point and the solids being retained in the water to be 105 carried off by it, thus preventing said solids

from being liberated into the atmosphere as is the case where ordinary flues and smoke stacks are provided.

Having thus fully described my invention, what I claim as new and desire to secure by Letters Patent is:

1. Smoke washing means, comprising an exhaust fan arranged to exhaust from the smoke outlet of a furnace, a pump arranged 10 to receive the exhaust from said fan, a source of water supply to said pump, whereby said pump is caused to mix said exhaust and water, and a closed reservoir for receiving the discharge from said pump, said reservoir being provided with an outlet for gases.

2. Smoke washing means, comprising an exhaust fan arranged to exhaust from the smoke outlet of a furnace, a series of pumps, 20 the first of said pumps being arranged to receive the exhaust from said fan, a source of water supply to said first pump, whereby said pump is caused to mix said exhaust and water, each successive pump in said series 25 being arranged to receive the mixed water and smoke from the preceding pump, and a closed reservoir for receiving the discharge from the last pump, said reservoir being provided with an outlet for gases.

3. Smoke washing means, comprising a reservoir for liquid, an exhaust fan arranged to exhaust from the smoke outlet of a furnace, a pump submerged in the liquid in said reservoir said pump being arranged to receive the exhaust from said fan and also to 30 pump liquid from said reservoir whereby said exhaust and water may be mixed, a closed reservoir for receiving the discharge from said pump, said closed reservoir being provided with an outlet for gases.

4. Smoke washing means, comprising a reservoir for liquid, an exhaust fan arranged to exhaust from the smoke outlet of a furnace, a pump submerged in the liquid in said 45 reservoir said pump being arranged to receive the exhaust from said fan and also to pump liquid from said reservoir whereby said exhaust and water may be mixed, a closed reservoir for receiving the discharge from said pump, said closed reservoir being provided with an outlet for gases.

5. Smoke washing means, comprising a reservoir for liquid, an exhaust fan arranged to exhaust from the smoke outlet of a furnace, a series of pumps the first of said 60 pumps being submerged in the liquid in said reservoir and being arranged to receive the exhaust from said fan, and also to pump liquid from said reservoir, whereby said exhaust and water may be mixed, each successive pump in said series being arranged to

receive the mixed water and smoke from the preceding pump, and a closed reservoir for receiving the discharge from the last pump, said reservoir being provided with an outlet for gases.

70

6. Smoke washing means, comprising a reservoir for liquid, an exhaust fan arranged to exhaust from the smoke outlet of a furnace, a series of pumps, the first of said pumps being submerged in the liquid in said 75 reservoir and being arranged to receive the exhaust from said fan and also to pump liquid from said reservoir, whereby said exhaust and water may be mixed, each successive pump in said series being arranged to receive the mixed water and smoke from the preceding pump, a closed reservoir for receiving the discharge from the last pump, said closed reservoir being mounted inside said first mentioned reservoir, screened openings in said closed reservoir communicating with said first reservoir, said closed reservoir being provided with an outlet for gases.

85

7. Smoke washing means, comprising an exhaust fan arranged to exhaust from the smoke outlet of a furnace, a pump arranged to receive the exhaust from said fan, a source of water supply to said pump, whereby said pump is caused to mix said exhaust and water, a closed reservoir for receiving the 95 discharge from said pump, said reservoir being provided with an outlet for gases, and means whereby said pump may be driven at a slightly higher speed than said fan.

90

8. Smoke washing means, comprising a 100 reservoir for liquid, an exhaust fan arranged to exhaust from the smoke outlet of a furnace, a pump submerged in the liquid in said reservoir, said pump being arranged to receive the exhaust from said fan and also to pump liquid from said reservoir, whereby said exhaust and water may be mixed, a closed reservoir for receiving the discharge from said pump, said closed reservoir being provided with an outlet for gases, and means 105 whereby said pump may be driven at a slightly higher speed than said fan.

110

9. Smoke washing means, comprising an exhaust fan arranged to exhaust from the smoke outlet of a furnace, a series of pumps, the first of said pumps being arranged to receive the exhaust from said fan, a source of water supply to said first pump, whereby said pump is caused to mix said exhaust and water, each successive pump in said series 115 being arranged to receive the mixed water and smoke from the preceding pump, a closed reservoir for receiving the discharge from the last pump, said reservoir being provided with an outlet for gases, and means whereby said pumps may be driven at a slightly higher speed than said fan.

120

10. Smoke washing means, comprising a reservoir for liquid, an exhaust fan arranged to exhaust from the smoke outlet of a fur- 125

- nace, a pump submerged in the liquid in said reservoir, said pump being arranged to receive the exhaust from said fan and also to pump liquid from said reservoir, whereby
5 said exhaust and water may be mixed, a closed reservoir for receiving the discharge from said pump, said closed reservoir being mounted inside said first mentioned reservoir, screened openings in said closed reservoir communicating with said first reservoir, said closed reservoir being provided with an outlet for gases, and means whereby said pump may be driven at a slightly higher speed than said fan.
- 10 11. Smoke washing means, comprising a reservoir for liquid, an exhaust fan arranged to exhaust from the smoke outlet of a furnace, a series of pumps, the first of said pumps being submerged in the liquid in said reservoir and being arranged to receive the exhaust from said fan, and also to pump liquid from said reservoir, whereby said exhaust and water may be mixed, each successive pump in said series being arranged to receive the mixed water and smoke from the preceding pump, a closed reservoir for receiving the discharge from the last pump, said closed reservoir being mounted inside said first mentioned reservoir, screened openings in said closed reservoir communicating with said first reservoir, said closed reservoir being provided with an outlet for gases, and means whereby said pumps may be driven at a slightly higher speed than said fan.
- 15 12. Smoke washing means, comprising a reservoir for liquid, an exhaust fan arranged to exhaust from the smoke outlet of a furnace, a series of pumps, the first of said pumps being submerged in the liquid in said reservoir and being arranged to receive the exhaust from said fan and also to pump liquid from said reservoir, whereby said exhaust and water may be mixed, each successive pump in said series being arranged to receive the mixed water and smoke from the preceding pump, a closed reservoir for receiving the discharge from the last pump, said closed reservoir being provided with an outlet for gases, and means whereby said pumps may be driven at a slightly higher speed than said fan.
